DOOR CLOSER BRAKE

Bert A. Quinn, St. Paul, Minn., assignor to Ideal Brass Works, Incorporated, St. Paul, Minn., a corporation of Minnesota

Filed Oct. 9, 1963, Ser. No. 314,930
2 Claims. (Cl. 16—66)

My invention relates generally to automatic door-closing mechanisms, and more particularly to spring-actuated door-closing devices which rely upon pneumatic pressures to counteract the action of the springs, whereby to impart orderly closing movements to the door.

Devices of the class above described normally include an elongated cylindrical casing in which is mounted a plunger-equipped piston, one end of the casing being securable to a door, and the extended end of the plunger to the door frame, or vice-versa.

Under unusual conditions, due to strong gusts of wind and the like, doors equipped with such devices are known to be thrown open against the action of the springs with such force as to damage both the door and the closure mechanism. To offset this, braking means have heretofore been provided for automatically checking such undesirable door-opening movements. However, such known means take effect progressively as the piston moves from one end of the cylinder toward the other end thereof. Consequently, one manually opening a door so equipped is required to exert additional and objectionable door-opening force thereagainst, even during initial opening movements.

The primary object of my invention is the provision of a novel braking mechanism which will not go into effect during the initial opening movements of the door so as to avoid any objectionable drag during normal manual door-opening movements. Under such an arrangement the automatic braking mechanism does not go into play until the latter part of the stroke of the piston in its travel from one end of the cylindrical casing to the other end thereof.

A further and highly important object of my invention is the provision of a device of the class described wherein the door is prevented from starting to close too fast, whereby to bring about a smoothness of closing action without over compressing the air within the cylinder to cause a rebound.

A still further object of my invention is the provision of a device of the class immediately above described wherein there is no loss of closing power as the door approaches latching position.

A further object of my invention is the provision of a device of the class above described which is inexpensive to produce, which incorporates a minimum of working parts, and which is positive and foolproof in its operation.

The above and still further objects of my invention will become apparent from the following detailed specification, appended claims, and attached drawings.

Referring to the drawings wherein like characters indicate like parts throughout the several views:

FIG. 1 is a view in horizontal section through a door casing and a door mounted therein showing my novel closure device in plan;

FIG. 2 is a view in axial section as seen from the line 2—2 of FIG. 1 on an enlarged scale;

FIG. 3 is a greatly enlarged view in axial section of a portion of the structure shown in FIG. 2, showing a different position of parts thereof;

FIG. 4 is an enlarged view in perspective of the brake shoe utilized in the structure of FIG. 2, portions thereof broken away; and

FIG. 5 is a view similar to FIG. 3, showing a modified embodiment.

2

Referring with greater particularity to the drawings, and initially to the preferred embodiment of FIGS. 1 to 4, inclusive, the elongated cylindrical casing of my novel door closer is identified by 10. Mounted for axial sliding movements within the casing 10, in sliding engagement with the inner side wall 11 thereof, is a piston identified in its entirety by 12 and, as shown, comprising primary and secondary piston sections 12a and 12b. Extending loosely through piston section 12b and fast on the axis of section 12a is a plunger rod 13, the outer end 14 of which projects loosely through an opening 15 in one end 16 of the casing 10. At its projected free end the plunger 13 is provided with suitable bracket means 17 for securing same to a door frame A; whereas the other end 18 of the casing 10 is provided with suitable bracket means 19 for securing same to the screen or storm door B.

Piston section 12a, as shown, is preferably formed from a pair of cooperating annular disks 20, 21 of specifically different cross sectional contour, and secured together at their radially inner limits and made fast on the inner end 13a of the plunger 13 by peening over the reduced end of the latter, as indicated at 22.

At their radially outer ends, the disk-like portions 20, 21 cooperate to define a radially outwardly opening annular groove 23 in which is received for limited axial sliding movements, while in engagement with the inner wall surface 11 of the casing 10, an O-ring 24. It will be noted that during axial movements of the piston 12 from the end 18 of the casing 10 toward the end 16 thereof that the O-ring 24 will be removed from engagement with a cam surface 25, defined by element 21, whereby to permit air freely to pass thereunder and outwardly through the port 26 in the element 20, see particularly FIG. 3. On the other hand, when the piston 12 is moved axially from the end 16 of the casing 10 toward the end 18 thereof, the O-ring 24 is forced to climb up upon the cam ring surface 25 and make sealing engagement with the inner wall 11 and the casing 10.

Because the element 21 of the piston section 12a and piston section 12b are formed from sheet metal stampings, same are separately formed. However, in the operation of my device, I wish it to be specifically understood that these parts could well be integrally formed.

In any event, a coil compression spring 26a loosely encompasses the inner end 13a of the plunger rod 13 with one end thereof in abutting relationship to the piston 12, as indicated at 27, and with the other end received in a counterbore 28 formed in a collar 29 slidably received on said plunger rod 13.

As shown particularly in FIG. 3, the collar 29 at its periphery is formed to define an annular cam surface 30 which tapers in the direction of the piston section 12b; whereas the piston section 12b is formed to define an annular cam surface 31 which tapers in the direction of the collar 29. Interposed between the cam surfaces 30, 31 of the collar 29 and piston section 12b, respectively, is an annular brake shoe 32, axially split as at 33 and having axially spaced converging cam surfaces 34, 35

which cooperate respectively with the cam surfaces 30, 31 when yielding bias is exerted upon the collar 29 by a coil compression spring 36 with sufficient force to overcome the compression value of coil compression spring 26. As shown, the coil compression spring 36 also encompasses the plunger rod 13 and has one end in abutting relationship with the collar 29 within an annular recess 37 and the other end in engagement with the restricted end 16 of the casing 10.

With the novel combination and arrangement of parts immediately above described, the coil compression spring 36, because of its length, normally biases the piston 12 and parts carried thereby toward end 18 of casing 10,

as shown in FIG. 2. However, because of the relative compressive values of the springs 36 and 26 when in said position, the piston element 12b becomes separated from the section 12a and exerts no braking pressure against the brake shoe 32. It might here be stated that during movements of the piston 12 from the end 16 toward the end 18 of the casing 10 that air is permitted to escape as desired from the end 18 through the medium of an adjustable valve, shown as being in the nature of a conventional vented screw 38.

When opening movements are imparted to the door B against the yielding bias of coil compression spring 36, the yielding bias of the coil spring 26 is progressively overcome during initial movements of the piston 12. However, at this point, and after a given distance of travel of the piston 12, determined solely by the relative length and values of the springs 26, 36, the two sections 12a, 12b of the piston 12 will come together and the cam surfaces 30, 31 of the collar 29 and piston 12 come into operative engagement with the respective cam surfaces 34, 35 of the brake shoe 32 and start to progressively exert greater radially outward braking pressure upon the cylindrical wall 11 of the casing 10. Such braking pressure stops movement of the piston 12 sufficiently in advance of the inner end 16 of the casing, or alternatively slows down the speed of piston 12, to prevent damage to either the door B or of my novel door-closing mechanism above described, during uncontrolled opening movements of door B, under conditions above described.

In the slightly modified structure of FIG. 5, wherein parts similar to the structure of FIGS. 1 to 4, inclusive, are similarly identified, the piston section 12c is shown as being in the nature of an annular washer, interposed between section 12a and the collar 29. Consequently, the brake shoe 32a is provided merely with one cam surface 34a, which is adapted to cooperate with the cam surface 30 of the collar 29. The operation of this structure is obviously identical to that of the structure FIGS. 1 to 4, inclusive.

My invention has been thoroughly tested and found to be entirely satisfactory for the accomplishment of the above objects; and while I have disclosed a preferred embodiment thereof, my invention may be capable of modification without departure from the scope and spirit of the appended claims.

What is claimed is:

1. In a pneumatic door closer:
  - (a) an elongated cylindrical casing,
  - (b) a piston slidably received within said casing and having an axially extended plunger rod projecting through one end thereof,
  - (c) said piston and the opposite end of said casing cooperating to define check valve means for regulating the rate of movement of said piston toward said opposite end of said casing, and

(d) means for progressively applying braking action to said piston as same moves from said other end of said casing to said one end thereof, said means comprising:

- (1) a collar slidably received on said plunger rod within said casing and defining a cam acting surface which tapers toward said opposite end of said casing,
- (2) a coil compression spring encompassing said plunger and interposed between said piston and said collar and yieldingly biasing same apart,
- (3) a second coil compression spring encompassing said plunger rod within said casing and interposed between said collar and said one end thereof and having a greater compression value than that of said first mentioned compression spring, and
- (4) an axially split annular brake shoe interposed between said piston and said collar and having a tapered cam acting surface on one side which cooperates with the reversely tapered cam acting surface on said collar, whereby to cause said brake shoe to engage the inner wall of said casing with progressively increasing braking pressure as said second mentioned spring progressively overcomes the force exerted by said first mentioned spring during movements of said piston from said opposite end of said casing toward said one end thereof,
- (5) the relative length and compression values of said compression springs coupled with the dimensions of said brake shoe being such as to delay the expanding braking pressure exerted by said collar upon said brake shoe during initial movements of said piston from said opposite end to said one end of said casing.

2. The structure defined in claim 1 in which said piston defines a second cam acting surface which tapers toward said one end of said casing and in which said brake shoe is also formed to define a reversely tapered cam acting surface which cooperates with said second cam acting surface on said piston to expand said brake shoe during said movements.
